UNITED STATES PATENT OFFICE.

JOHN JOSEPH MOORE, OF SOUTH CHARLESTON, OHIO.

SIGNPOST.

1,391,001.

Specification of Letters Patent. Patented Sept. 20, 1921.

Application filed April 10, 1920. Serial No. 372,841.

To all whom it may concern:

Be it known that I, JOHN J. MOORE, a citizen of the United States, residing at South Charleston, in the county of Clark and State of Ohio, have invented a new and useful Signpost, of which the following is a specification.

This invention relates to sign posts.

An object is to provide a sign post composed entirely of metal and having a separate base portion which is adapted to be driven into the ground as a unit and into which may be inserted the post proper to be permanently connected thereto in such manner as to prevent its accidental dislodgment, but which by the proper application of a specially constructed key, may be readily detached therefrom for use elsewhere, or for the application of another sign.

Another object is to provide means to be used in conjunction with the base portion or member thereof to prevent battering or marring the same when driving it into the ground. A further object is to provide a strong and durable detachable post of this character which will withstand hard usage, and which is so constructed as to exclude the entrance of water through the joints necessarily present in such devices.

A full and complete understanding of the invention may be obtained from a consideration of the following detailed description taken in connection with the accompanying drawing forming part of this specification, with the understanding, however, that the invention is not confined to any strict conformity with the showing of the drawing but may be changed and modified, so long as such changes and modifications mark no material departure from the salient features of the invention as expressed in the appended claims.

In the drawing, in which similar reference characters designate corresponding parts throughout the several figures:—

Figure 1 is a side elevation of a sign post constructed in accordance with the invention and shown partly broken away;

Fig. 2 is an enlarged vertical sectional view illustrating the interlocking engagement between the post proper and the base member, the latter being shown partly in elevation;

Fig. 3 is a horizontal section on the line 55 3—3 of Fig. 2;

Fig. 4 is a similar view on the line 4—4 of Fig. 2;

Fig. 5 is a detail side elevation of the post and the base member taken at right angles to Fig. 1 and drawn on the same scale; 60

Fig. 6 is a side elevation partly in section of the driving cap used to drive the base member into the ground;

Fig. 7 is a side view of the key used to detach the post from the base member; 65

Fig. 8 is a detail perspective view of the plate used as a closure to render the key hole water tight.

Referring to drawing, there is shown a tubular sign post proper 1, which may be of any desired diameter and length, and which may be formed of ordinary tubing found on the market. At the top this tube or post may be provided with any well-known form of sign, which may be attached thereto in any desired manner. The lower portion of the tube is reduced, as at 2, the metal forming the walls thereof being somewhat thinner and having an undercut shoulder 3. 70

At diametrically opposite points the reduced walls of the post are provided with longitudinally extending slots 4, each having a flared mouth or entrance opening, at 5, coincident with the lower edge of the tube and for a purpose to be explained. 80

At the upper or closed ends, each slot 4 is provided with a right-angularly disposed or horizontal branch 6, terminating in a seat 7 extending upwardly therefrom and in the same direction as the main slot 4 or longitudinally of the post 1, thus forming a pair of opposed bayonet slots relatively so disposed as to be capable of receiving and of locking therein certain members of a co-acting part to be later described. 90

At the point of juncture of the main entrance slot 4 and the horizontally disposed branch slot 6, a longitudinally disposed spring tongue 8 is formed of the metal of the reduced tubing by providing a slit 9 in 100 spaced relation to the said slot 4 and parallel thereto, the lower or closed end of the slit 9 being located substantially mid-way between the open flared end 5 and the branch 6. The normal tendency of this tongue 8 is to stand vertically, but it may, by pressure, be flexed inwardly toward the center of the said post. 105

A base member 10 is provided for use in conjunction with the post 1, and is adapted to be driven into the ground a sufficient dis- 110

tance to withstand any strain to which the post may be subjected, the lower portion of the same being preferably of solid metal as indicated at 11, and being preferably triangular in cross section, so as to prevent the turning of the same after being driven into the ground.

The upper tubular portion or socket 12 of the base member has an internal diameter to 10 snugly fit the reduced lower end portion 2 of the post 1, and is of a depth substantially equal to the length thereof. The tubular portion 12 is provided at its upper open end with an integral annular collar 13 extending 15 outwardly and having its upper face inclined in conformity with the under face of the shoulder 3 which, when the post 1 is fully introduced into the base member 10, will effectually prevent the entrance of water into 20 the joint. The lower face of the collar is substantially horizontal and provides means by which the base member may be removed from the ground, when desired.

The tubular portion 12 of the base member is provided on its inner wall, at diametrically opposite points, with inwardly-directed lugs 14 located below the upper inclined face of the annular collar 13 a distance equal to the distance between the seats 30 7 and the undercut shoulder 3 of the post member. These lugs 14 each have one face beveled so that, when the post is introduced into the tubular upper end of the base member, the lugs will freely enter the flared entrance openings 5 of the longitudinal slots 4 and, upon reaching the upper ends of the said slots may, by turning the post, be forced past the upstanding tongues 8 by bending the same inwardly toward the center of the post, and may then move into the branch slots 6 to a position to be then moved longitudinally into the seats 7, at which time the upper beveled end of the base member is snugly seated beneath the 45 beveled lower face of the shoulder 3. It will be seen that the straight radially disposed faces of the inwardly-directed lugs 14 carried by the base member will effectually prevent the removal of the post therefrom, by 50 reason of the fact that the same will come into abutting contact with the tongues 8 when an effort is made to turn the post within the base member.

In order to permit the post to be removed 55 from its engagement with the base member, when desired, as for changing signs, the tubular upper portion of the base member is provided with a pair of oppositely disposed key holes 15 located directly below the inwardly-directed lugs 14, and in a position opposite the free flexible ends of the spring tongues 8, and a pair of keys 16 (Fig. 7), are introduced through the key holes 15 until the end of the key strikes the wall of the post. 60 65 Then by turning each key the pointed and

beveled lug 17 thereof will wedge in between the inner wall of the base member and the outer face of the spring tongue, which may be slightly beveled to facilitate such wedging section, and the latter will be forced inwardly and out of the path of movement of the lugs 14 when the post is rotated in the proper direction, whereupon the latter may then be readily removed.

When the parts have been locked together 75 and the key removed, the said key holes 15 may each be closed by a removable closure plate 18, which is arcuately curved in conformity with the outer surface of the tubular upper portion of the base member, and which is adapted to be slid into a properly grooved marginal bead 19 surrounding three sides of the closure plate.

The annular collars 13 have their lower faces arranged at right angles to the outer 85 face of the base member and are adapted to provide a shoulder or abutment for a chain or cable to be placed in surrounding relation to the base member, after the post has been removed, when it is desired to pull the 90 base member from the ground.

In order to protect the upper knife edge of the tubular socket portion of the base member, when driving the same into the ground, a driving cap-plate 20 is provided, 95 composed preferably of solid metal and having a reduced extension 21 of a diameter to fit within the upper end of the base member, and an undercut shoulder 22 corresponding to the upper beveled face of the annular collar 13 and adapted to fit over the collar to protect its edge when the upper face of the cap-plate 20 is hammered.

From the foregoing it will be seen that a strong and durable interchangeable sign 105 post has been provided, which may be readily manufactured from ordinary stock material and at a low cost, that the same is easily operated to affix a sign thereto or to remove the same when desired. It is also 110 clear that the device may be found useful for other purposes; for example, it could be employed as a fence post.

What is claimed is:

1. A sign post comprising a base member 115 adapted to be driven into the ground and having a socket in its upper end, a pair of inwardly-directed beveled lugs provided within the socket at diametrically opposite points, and a detachable tubular post having 120 its lower end to fit within the socket, said tubular post being provided with oppositely disposed bayonet slots adapted to receive the lugs of the base member, said slots having angular branches communicating with seats, 125 and spring tongues formed integrally with the tubular post and extending partly across the angular branches of the bayonet slots and adapted to be pressed inwardly by the beveled faces of the said lugs to permit the 130

same to reach the said seats upon turning the post within the base, said tongues preventing the post from being turned in the opposite direction.

- 5 2. A sign post comprising a base member adapted to be driven into the ground and having a socket in its upper end, a pair of inwardly directed beveled lugs provided within the socket at diametrically opposite 10 points, the walls of said socket having a key hole beneath each lug, and a detachable tubular post having a reduced lower end to fit within the socket and an overhanging shoulder to bear upon the upper end of the base 15 member, said tubular post being provided with oppositely disposed bayonet slots adapted to receive the lugs of the base member, said slots having angular branches communicating with seats, and spring tongues 20 formed integrally with the tubular post and extending partly across the angular branches of the bayonet slots and adapted to be pressed inwardly by the beveled faces of the said lugs to permit the same to reach the 25 said seats upon turning the post within the base, said tongues preventing the post from being turned in the opposite direction.

3. A sign post comprising a base member

adapted to be driven into the ground and having a socket in its upper end and an integral collar extending out from the upper end of the socket, said collar having its upper face inclined and its lower face substantially horizontal, a tubular post having its lower end reduced to fit within the socket of 30 the base member, and having a shoulder at the upper part of said reduced portion, said shoulder being undercut to engage with the upper face of said collar, and means within the socket and reduced portion for detachably connecting the post to the base member.

4. In a sign post the combination with a base member adapted to be driven into the ground and having a socket in its upper end, a keyhole in said socket, a detachable tubular post having its lower end fitted in said socket, interlocking means carried by the base member and post and concealed and inclosed within said socket and the lower end of said post, said means serving to lock the 45 post to said base member, and means whereby said interlocking means may be released by a key inserted in the key hole.

In testimony that I claim the foregoing as my own I have hereto affixed my signature. 50
JOHN JOSEPH MOORE. 55
